Richard Schuck

UNITED STATES PATENT OFFICE.

JOSEPH R. ANDERSON, OF PHILADELPHIA, PENNSYLVANIA.

CLOTHES-HOOK.

SPECIFICATION forming part of Letters Patent No. 395,108, dated December 25, 1888.

Application filed March 11, 1886. Serial No. 194,820. (No model.)

To all whom it may concern:

Be it known that I, JOSEPH R. ANDERSON, a citizen of the United States, residing in the city and county of Philadelphia, and State of Pennsylvania, have invented a new and useful Improvement in Clothes-Hooks, of which the following is a specification, reference being had to the accompanying drawings, which form part thereof.

10 My invention is adapted chiefly for wardrobes and closets, and is intended to increase the facility with which clothes may be taken from the hooks. Heretofore the usual method has been simply to fasten a number of hooks 15 to the top of the wardrobe or closet, and on these the clothes are hung. Now, it is evident that there is great difficulty and trouble in removing articles from the inner hooks or those which are farthest away from the door, 20 owing to the obstruction offered by the clothes on the front hooks. My invention entirely removes this difficulty by having a series of hooks fastened, not to the top of the wardrobe, but in a circular plate or ring, which is 25 attached to the top by a pivot and is free to revolve. Now, it will be seen that articles on the inner hooks, by a simple revolution of the plate, may be brought front and thus removed without difficulty.

30 The circular plate or ring to which the hooks are fastened may be provided with rollers to increase the ease of rotation, and to the top of the wardrobe may be attached a plate on which these rollers may run. Now, it is evident that the form of this circular revolving 35 apparatus may be varied in many ways without in the least departing from the invention, and the particular form shown in the drawings is only one of the most convenient. This 40 form consists of a circular metal plate in a plane slightly above that of a ring. The bolt passes through this plate into the wardrobe top, holding the apparatus and allowing it to revolve. The plate next to the wardrobe may 45 be fastened by nails or pins, or it may be held in position simply by the large pin by which the revolving apparatus is attached.

In the drawings, Figure 1 is a front elevation 50 of a wardrobe with one of the doors open and showing my improved clothes-hooks attached therein. Fig. 2 is a vertical section through the clothes-hook turn-table on line

y y, and Fig. 3 is a sectional plan view of part of same on line x x.

A is the wardrobe proper.

C is the upper wood-work thereof, forming the loop, and B is the turn-table attached thereto. This turn-table consists of a framework, D, preferably of light open metal work, in which the central portion is somewhat 60 raised to form a bearing against the shelf or the top C of the wardrobe or closet, or a plate, F, arranged next thereto; or, if desired, small rollers G may be located in the upper part of the turn-table D, or in the plate F, to reduce 65 the friction between the said turn-table and plate when the turn-table is loaded with clothes.

E is the pivoted portion which connects the turn-table with the upper part of the closet 70 or wardrobe, and it also retains the plate F in the central position. If desired, the plate F may be rigidly secured to the wood-work C by screws, or it may rest upon the rollers and form a bed-plate for them to run upon, as 75 its vertical contact when pressed against the wood-work will prevent its rotating when the rollers are pressed up in contact with it, due to unequal loading of the turn-table hooks.

The turn-table is provided with a series of 80 depending hooks of any desired construction, which may be detachably connected thereto on the outer rim; or, if desired, this rim may be cast with hooks, as indicated in dotted lines in Fig. 2.

I do not limit myself to any particular specific construction, as the particular form or shape of the turn-table is immaterial, and in place of a central pivot it may be supported in hangers D', which, if desired, may be furnished with anti-friction supporting-rollers, as is also indicated in dotted lines, Fig. 2, upon which the outer periphery of the turn-table rests; and in place of supporting the turn-table in either of these methods described 90 95 the depending bolt E may be provided with a plate or frame, e, and anti-friction rollers or wheels g, upon which the turn-table rests, as is also shown in dotted lines, Fig. 2. Therefore, while I prefer the construction shown, I 100 do not limit myself thereto.

Having now described my invention, what I claim as new, and desire to secure by Letters Patent, is—

1. The combination of the turn-table frame having a series of clothes-hooks arranged on or near its periphery and provided with anti-friction wheels to reduce the friction of contact with its support, and of a stationary anti-friction plate attached to the underside of the top of the wardrobe and against which said anti-friction wheels run, with a central pivot-bolt for attachment to the top of the wardrobe or closet, substantially as and for the purpose specified.
2. In a wardrobe or closet, the upper and

inner surface thereof, combined with an anti-friction plate, turn-table frame having hooks on or near its periphery, and central pivot-bolt passing through the anti-friction plate and turn-table frame, centering the plate and supporting the frame, substantially as described. 15

JOSEPH R. ANDERSON.
